UNITED STATES PATENT OFFICE

110,811

DESIGN FOR A SHOE

John S. Kent, Jr., Brockton, Mass., assignor to
M. A. Packard Company, Brockton, Mass., a
corporation of Massachusetts

Application June 25, 1938, Serial No. 78,057

Term of patent 3½ years

To whom it may concern:

Be it known that I, John S. Kent, Jr., a citizen of the United States, residing at Brockton, in the county of Plymouth and State of Massachusetts, have invented a new, original, and ornamental Design for a Shoe, of which the following is a specification, reference being had to the accompanying drawing, forming part thereof.

In the drawing the figure is a side elevation of a shoe showing my new design. Both sides of

the shoe present substantially the same appearance.

As the design is applicable to shoes of various shapes and styles the representation of shoe is merely conventional, for showing an application of the design.

I claim:

The ornamental design for a shoe, as shown and described.

JOHN S. KENT, JR.
